HATCH CONSTRUCTION

Paul E. Finger, Gary, Ind., assignor to Standard
Railway Equipment Manufacturing Company,
a corporation of Delaware

Application July 5, 1940, Serial No. 344,012

16 Claims. (Cl. 108—5.4)

This invention relates to the hatch constructions of metal car roofs of the type wherein the hatch-ways are arranged in pairs one on each side of the roof and are defined by metal hatch frames that extend above the level thereof. The invention has for its principal object to increase the strength and rigidity of the roof between hatch frames and to brace and strengthen the portions of the hatch frames located above the general level of the roof. Other objects are to utilize the hatch frames as part of the roof covering, to increase the space available beneath the roof for insulation and to provide for simplicity and cheapness of construction and compactness of design. The invention consists in the hatch construction and in the parts and combinations and arrangements of parts hereinafter described and claimed.

In the accompanying drawings, which form part of this specification and wherein like symbols refer to like parts wherever they occur,

Fig. 1 is a plan view of a portion of a metal car roof provided with a hatch construction embodying my invention.

Fig. 2 is an enlarged partial vertical transverse section through the roof, the section being taken through the hatchways on the line 2—2 in Fig. 1.

Fig. 3 is a partial vertical longitudinal section through the roof, the section being taken through one of the hatchways on the line 3—3 in Fig. 1.

Fig. 4 is a partial vertical longitudinal section through the roof at the ridge on the line 4—4 in Fig. 1.

Fig. 5 is a vertical transverse cross-section through the eaves portion of the roof on the line 5—5 in Fig. 1.

Fig. 6 is a fragmentary plan view of the roof in the region of one of the ridge corner portions of one of the hatch frames, said corner portion being shown in horizontal section.

Fig. 7 is a vertical section on the line 7—7 in Fig. 6.

Fig. 8 is a vertical transverse section through the eaves portion of the roof, showing a modified form of hatch construction.

Fig. 9 is a vertical longitudinal section on the line 9—9 in Fig. 8.

Fig. 10 is a vertical transverse section, similar to Fig. 2, showing another modification; and

Figs. 11 and 12 are partial vertical longitudinal sections on the lines 11—11 and 12—12, respectively, in Fig. 10.

In the construction shown in Figs. 1 to 7, inclusive, of the accompanying drawings, my invention is shown embodied in a railway car roof

comprising metal roof sheets A that span from side plate B to side plate B of the car and have depending end or eaves flanges 1 that overhang and are riveted or otherwise rigidly secured flatwise to the outer sides of the upstanding inner flanges 2 of said side plates. These main or full length roof sheets A are connected along their adjacent side margins by rigid upstanding seams C comprising upstanding flanges 3 along said margins that are straddled by seam caps 4 that are riveted or otherwise secured to said flanges and are turned down over the depending eaves flanges 1 of said roof sheets and are riveted or otherwise rigidly secured thereto and to the upstanding flanges 2 of the side plates B.

Between adjacent roof seams C, the two full length roof sheets A are spaced apart to receive therebetween a pair of metal hatch frames D that are spaced apart on opposite sides of the roof. These two hatch frames extend above and below the roof sheets A with their lower end portions supported in openings provided therefor in a framework comprising spaced carline members 5 connected by spaced cross-members 6, said members preferably comprising metal angle bars disposed with one of their flanges down to define the hatch frame receiving openings in said framework and with their other flanges facing outwardly in flush alinement to form a continuous supporting surface around each of said openings. The cross-members 6 have their ends welded or otherwise secured, as at 7, to the carline members 5. The hatch frames D are secured to the cross-members 6 by welds 8, which extend continuously along the lower edges thereof, and to the carline members 5 by spaced welds 9 along the lower edges of said hatch frames. The ends of the carline members 5 are rigidly secured to the side plates B by angle brackets 10 having one leg welded, as at 11, to the depending flanges of a carline member and the other leg riveted to the inner face of the upstanding flange 2 of a side plate. As shown in the drawings, the spaced apart margins of the full length roof sheets A are supported on the top flanges of the carline members 5 and are provided with upstanding edge flanges 12 that are disposed flush with the depending flanges of said member and extend from eaves to eaves of the roof and are turned down over the side plates with the depending eaves flanges 1 of said sheets.

As shown in the drawings, the space or opening defined by the upstanding side marginal flanges 12 of the spaced full length roof sheets A and the opposing sides of the spaced hatch frames

D is covered by a ridge roof sheet E; and eaves sheets F cover the spaces or openings between said flanges from said hatch beams to the side plates B. The ridge sheet E has its body portion disposed above the general plane of the roof and has its opposite side margins flanged downwardly to form depending side walls or flanges 13 and thence outwardly to form outstanding base flanges 14. The depending side walls 13 of this inverted channel-shaped ridge sheet E overhang and are riveted or otherwise rigidly secured to the upstanding flanges 12 of the sheets A, with the base flanges 14 seated on the body portion thereof. The ridge sheet E has upstanding end flanges 15 that are riveted or otherwise rigidly secured flatwise to the opposing sides of the hatch frames D, said flanges being further secured to said walls by continuous edge welds 16. At the corners of the hatch frames D, the side walls thereof are secured together by welds 17, and the joints between the corners of the ridge sheet E and the adjacent ridge corners of the hatch frames D are filled with weld metal 18. At their ends, the depending side walls 13 of the ridge sheet E are secured by edge welds 19 to the sides of the upstanding side marginal flanges 12 of the full length roof sheets A. The eaves sheets F have depending eaves flanges 20 which, like the depending eaves flanges 1 of the main sheets A, are riveted or otherwise rigidly secured to the upstanding inner flanges 2 of the side plates B. Said eaves sheets also have upstanding flanges 21 at their inner ends that are riveted or otherwise secured flatwise to the adjacent side walls of the hatch frames and are further secured thereto by edge welds 22 along the tops of said last mentioned flanges. Said eaves sheets also have upstanding side marginal flanges 23 that abut flatwise against the flanges 12 of the sheets A and are turned down with the eaves flanges 20 over the side plates. The abutting flanges 12 and 23 are rigidly secured together preferably by welds 24 along the flush upper edges thereof. The upstanding flanges 12 of the full length sheets A are riveted flatwise to the adjacent side walls of the metal hatch frames D and are also further secured thereto by edge welds 25 extending along the tops of said flanges.

By the arrangement described, the hatch frames D are sustained by the framework of the carline members 5 and cross members 6 located below the roof and also by the flanged side margins 12 of the full length roof sheets A that are supported on said carline members and extend along and are rigidly secured to two opposite walls of each of said hatch frames. The eaves sheets F are also supported on the framework and are rigidly secured to the full length sheets A and to the side plate B; and the roof sheets A, E and F all have rigid waterproof connections with the walls of the hatch frames. The hatch frames extend a considerable distance above the roof, thus preventing water from splashing over the tops of said frame. The ridge sheet, being located above the general level of the roof serves as a combined strut and tie between the two hatch frames and thus stiffen and strengthen the upper portions thereof against lateral shocks. At the same time, this higher elevation of the ridge sheet considerably increases the modulus of resistance of the roof between hatch frames, thereby increasing the vertical strength of the roof at the ridge. In the modification shown in Figs. 8 and 9, the eaves sheets are dispensed with and the space between the hatch frame D' and the side plate B is cov-

ered by a lateral extension 26 of the outer side wall of the hatch frame. The hatch frame extension 26 extends outwardly in conformity with the slope of the roof and terminates in a depending eaves flange 27 that is riveted or otherwise secured flatwise to the outer face of the upstanding inner flange 2 of the side plate B. As shown in Fig. 9, this roof covering extension 26 of the hatch frame is secured by an edge weld 28 to the adjacent sides of the carline members 5; and the flat side margins of the full length sheets A' overlap the adjacent margins of said extension and are secured thereto by edge welds 29.

In the construction shown in Figs. 10, 11 and 12, the invention is shown embodied in an insulated car roof. In this construction, the hatch frame supporting framework comprises carline members 5a and cross connecting members 6a in the form of angle bars whose hatch opening defining flanges extend upwardly above the general level of the roof. As shown in Fig. 10, the sides of the hatch frame that extend longitudinally of the roof are riveted or otherwise secured to the inner faces of the upstanding inner flanges of the cross frame members 6a and are notched to accommodate the carline members 5a; and two remaining side walls of said hatch frame are made in upper and lower sections, the upper section 30 being riveted or otherwise secured to the outer faces of the upstanding flanges of said carline members and the lower sections 31 having their upper edges welded or otherwise secured to the lower inside corners of said carline members. The eaves sheet F has its upstanding inner flange 21 riveted to the upstanding flange of the outermost cross frame member 6a; and the ridge sheet E' has depending side marginal flanges 13a that extend downwardly between the upstanding flanges of the carline members and the upstanding flanges 12 of the full length sheets A, all of said flanges being riveted or otherwise rigidly secured together. The flanged side margins 12 of the sheets A rest on the outstanding bottom flanges of the carlines 5a; and the ridge sheet has upstanding end flanges 15a riveted and welded to the adjacent sides of the two hatch frames.

What I claim is:

1. A railway car comprising a roof and a pair of spaced hatch frames embodied in said roof and extending thereabove, the portion of said roof located between said hatch frames being disposed above the general level of said roof.
2. A railway car comprising a metal roof and a pair of spaced metal hatch frames embodied in said roof and extending thereabove, said roof being offset upwardly from hatch frame to hatch frame to form a rigid cross-connection therebetween above the general level of said roof.
3. A railway car comprising a metal roof and a pair of metal hatch frames embodied in said roof and extending thereabove and spaced apart on opposite sides of the ridge thereof, said roof being offset upwardly above the general level thereof from hatch frame to hatch frame.
4. A railway car comprising side plates, a metal roof supported on said side plates, and a pair of metal hatch frames embodied in said roof and extending thereabove and spaced apart on opposite sides of the ridge thereof, said roof being offset upwardly above the general level thereof from hatch frame to hatch frame, said hatch frames having the walls thereof nearest said side plates extended outwardly and secured

thereto to constitute the portions of the roof between said walls and said side plates.

5. A car roof comprising a plurality of metal roof sheets arranged to provide a pair of hatch openings disposed one on each side of the ridge, metal hatch frames rigidly mounted in the respective openings and extending above said roof, one of said sheets being located between said hatch frames and disposed above the level of the remaining sheets.

6. A car roof comprising side plates, metal roof sheets extending from side plate to side plate and spaced apart longitudinally thereof, a pair of metal hatch frames mounted in the space between said roof sheets and spaced apart one on each side of said roof, and a third roof sheet covering the space between said spaced roof sheets from hatch frame to hatch frame and rigidly secured thereto and to said spaced sheets, said third roof sheet being disposed at a higher elevation than said spaced sheets.

7. A car roof comprising side plates, metal roof sheets extending from side plate to side plate and rigidly secured thereto and spaced apart longitudinally thereof, a pair of metal hatch frames mounted in the space between said roof sheets and spaced apart one on each side of said roof, metal eaves sheets covering said space between said side plates and hatch frames and rigidly secured thereto and to said spaced sheets, and a metal ridge sheet covering the space between said spaced roof sheets from hatch frame to hatch frame and rigidly secured thereto and to said spaced sheets, said ridge sheet being disposed at a higher level than said spaced sheets and said eaves sheets.

8. A car roof comprising metal roof sheets extending from eaves to eaves thereof and spaced apart longitudinally of the car, a pair of metal hatch frames mounted in the space between said roof sheets and spaced apart one on each side of said roof, metal eaves sheets covering the space between said spaced roof sheets from the hatch frames to the eaves of the roof and rigidly secured to said spaced sheets and to the respective hatch frames, and a metal ridge sheet covering the space between said spaced roof sheets from hatch frame to hatch frame and rigidly secured thereto and to said spaced sheets, said ridge sheet being disposed above the general level of said spaced sheets and said eaves sheets.

9. A car roof comprising metal roof sheets extending from eaves to eaves thereof and spaced apart longitudinally of the car, a pair of metal hatch frames mounted in the space between said roof sheets and spaced apart one on each side of said roof, and a metal ridge sheet covering the space between said spaced roof sheets from hatch frame to hatch frame and rigidly secured thereto and to said spaced sheets, said ridge sheet being disposed at a higher level than said spaced sheets, the remote walls of said hatch frames having lateral extensions that cover the space between said spaced sheets between the hatch frames and the eaves of the roof and are rigidly secured to said spaced roof sheets.

10. A car roof comprising metal roof sheets extending from eaves to eaves thereof and spaced apart longitudinally of the car, a pair of metal hatch frames mounted in the space between said roof sheets and spaced apart one on each side of said roof, and a metal ridge sheet covering the space between said spaced roof sheets from

75 hatch frame to hatch frame, said spaced sheets having flanges along their spaced margins that are rigidly secured to the adjacent side walls of said hatch frames, said ridge sheet having body portions disposed above the level of said spaced roof sheets and side flanges that are rigidly secured to said side marginal flanges of said spaced sheets from hatch frame to hatch frame and end flanges that are rigidly secured to the opposing side walls of said hatch frames.

11. A car roof comprising metal roof sheets extending from eaves to eaves thereof and spaced apart longitudinally of the car, a pair of metal hatch frames mounted in the space between said roof sheets and spaced apart one on each side of said roof, said spaced sheets having upstanding flanges that extend from end to end thereof along their spaced margin and are rigidly secured to the adjacent side walls of said hatch frames, metal eaves sheets covering the space between said spaced sheets from the hatch frames to the eaves of the roof, said eaves sheets having upstanding side flanges that are rigidly secured to the upstanding flanges of said spaced sheets and upstanding flanges that are rigidly secured to the adjacent walls of said hatch frames, and a metal ridge sheet covering the space between said spaced roof sheets from hatch frame to hatch frame, said ridge sheet having a body portion disposed above the level of said spaced roof sheets, depending side flanges that overhang and are rigidly secured flatwise to said upstanding side marginal flanges of said spaced sheets from hatch frame to hatch frame and upstanding end flanges that are rigidly secured flatwise to the opposing side walls of said hatch frames.

12. A car roof comprising metal roof sheets extending from eaves to eaves thereof and spaced apart longitudinally of the car, a pair of metal hatch frames mounted in the space between said roof sheets and spaced apart one on each side of said roof, said spaced sheets having upstanding flanges along their spaced margin and are rigidly secured flatwise to the adjacent side walls of the hatch frames, and a metal ridge sheet covering the space between said spaced roof sheets from hatch frame to hatch frame, said ridge sheet having a body portion disposed above the level of the spaced roof sheets, depending side walls that overhang and are rigidly secured to said upstanding side marginal flanges of said spaced sheets from hatch frame to hatch frame, outstanding base flanges at the lower edges of said side walls and upstanding end flanges that are rigidly secured flatwise to the opposing side walls of said hatch frames, the eaves opposing side walls of said hatch frame having lateral extensions that cover the space between said spaced sheets from the hatch frames to the eaves of the roof and are rigidly secured to the adjacent margins of said spaced sheets.

13. A car roof comprising spaced metal roof sheets, a metal hatch frame disposed in the space between said roof sheets and metal frame members extending along the spaced margins of said roof sheets, said members having base portions disposed beneath said margins and upstanding flanges extending above the level of said roof sheets inside said hatch frame.

14. A car roof comprising spaced metal roof sheets with upstanding flanges along their spaced margins, a metal hatch frame disposed in the space between said spaced marginal flanges and rigidly secured thereto, metal angle members extending along said spaced margins with one flange

therebeneath and with the other flange extending upwardly inside said hatch frame and rigidly secured thereto.

15. A car roof comprising metal roof sheets extending from eaves to eaves thereof and spaced apart longitudinally of the car, a metal hatch frame mounted in the space between said roof sheets, said spaced sheets having upstanding flanges along their spaced margins rigidly secured to the adjacent side walls of the hatch frames, and a supporting framework comprising spaced carline members extending along the flanged margins of said spaced sheets, said carline members comprising metal angles having one flange extending upwardly above the general level of the roof and secured to adjacent sides of said hatch frames and the other flange extending beneath said flanged margins of said spaced sheets.

16. A car roof comprising metal roof sheets extending from eaves to eaves thereof and spaced apart longitudinally of the car, a pair of metal hatch frames mounted in the space between said roof sheets and spaced apart one on each side of said roof, a metal ridge sheet covering the space between said spaced roof sheets from hatch frame to hatch frame, said spaced sheets having upstanding flanges that extend from end to end thereof along their spaced margins and are rigidly secured to the adjacent side walls of the hatch frames, said ridge sheet having depending

flanges that overhang and are rigidly secured to said upstanding side marginal flanges of said spaced sheets from hatch frame to hatch frame and having upstanding end flanges that are rigidly secured to the opposing side walls of said hatch frames, eaves sheets covering the space between said space sheets from the hatch frames to the eaves of the roof, said eaves sheets having upstanding side flanges that are rigidly secured to the upstanding flanges of said spaced sheets and upstanding flanges that are rigidly secured to the adjacent walls of said hatch frames, and a supporting framework comprising spaced carline members extending along the flanged margins of said spaced sheets and spaced cross members extending from carline member to carline member, some of said cross members being disposed beneath and affording support for said eaves sheets, said carline and frame members comprising metal angles, having one flange extending upwardly above the general level of the roof, and the other flange extending outwardly beneath the roof, the upstanding flanges of the carline members extending upwardly inside said hatch frames and ridge sheets and the corresponding flanges of said cross members extending upwardly along the outer side faces of said hatch frames.

PAUL E. FINGER.
